US00D837025S

(12) **United States Design Patent** (10) **Patent No.:** **US D837,025 S**
Demers et al. (45) **Date of Patent:** **** Jan. 1, 2019**

(54) **TOOL HANDLE**(71) Applicant: **LOWE'S COMPANIES, INC.**,
Mooresville, NC (US)(72) Inventors: **Brian Joseph Demers**, Huntersville,
NC (US); **Joseph Allen Berlepsch**,
Mooresville, NC (US)(73) Assignee: **Lowe's Companies, Inc.**, Mooresville,
NC (US)(**) Term: **15 Years**(21) Appl. No.: **29/601,602**(22) Filed: **Apr. 24, 2017****Related U.S. Application Data**(62) Division of application No. 29/530,843, filed on Jun.
19, 2015, now Pat. No. Des. 788,564, which is a
division of application No. 29/472,387, filed on Nov.
12, 2013, now Pat. No. Des. 735,553, which is a
division of application No. 29/406,984, filed on Nov.
21, 2011, now Pat. No. Des. 696,596, which is a
division of application No. 29/390,549, filed on Apr.
26, 2011, now Pat. No. Des. 652,702, which is a
division of application No. 29/361,192, filed on May
6, 2010, now Pat. No. Des. 639,132, which is a
division of application No. 29/318,754, filed on May
27, 2008, now Pat. No. Des. 617,623, which is a
division of application No. 29/249,420, filed on Oct.
5, 2006, now Pat. No. Des. 589,322.(51) **LOC (11) Cl.** ..... **08-05**(52) **U.S. Cl.**USPC ..... **D8/107**(58) **Field of Classification Search**USPC D8/107, 68, 69, 62, 97; D23/225, 250;

Primary Examiner — Paula Allen Greene

(74) Attorney, Agent, or Firm — Moore & Van Allen PLLC; W. Kevin Ransom

(57) CLAIM

The ornamental design for a tool handle, as shown and described.

DESCRIPTION

FIG. 1 is a perspective view of a tool handle according to the present invention;

FIG. 2 is an elevational view of the front side of the tool handle of FIG. 1;

FIG. 3 is an elevational view of the rear side of the tool handle of FIG. 1;

FIG. 4 is a plan view of the top side of the tool handle of FIG. 1;

FIG. 5 is a plan view of the bottom side of the tool handle of FIG. 1;

FIG. 6 is an elevational view of the left side of the tool handle of FIG. 1; and,

FIG. 7 is an elevational view of the right side of the tool handle of FIG. 1.

The broken lines shown in the drawings illustrate unclaimed portions of the tool handle and environmental structure, and form no part of the claimed design.
